UNITED STATES PATENT OFFICE

GUSTAVE HUBACH, OF SPRINGFIELD, MASSACHUSETTS, ASSIGNOR TO CHARLES A. DANA AND JOHN B. PIERCE, AS RECEIVERS OF THE FISK RUBBER COMPANY, OF CHICOPEE FALLS, MASSACHUSETTS, A CORPORATION OF MASSACHUSETTS

DESIGN FOR A TIRE

Application filed June 11, 1932. Serial No. 44,054. Term of patent 14 years.

To all whom it may concern:

Be it known that I, GUSTAVE HUBACH, a citizen of the United States residing at Springfield, in the county of Hampden and State of Massachusetts, have invented a new, original, and ornamental Design for a Tire, of which the following is a specification, reference being had to the accompanying drawing, forming part thereof.

Fig. 1 is a fragmentary plan view of a tire embodying the design;

Fig. 2 is a fragmentary cross-section thereof on line 2—2 of Fig. 1;

Figure 3 is a side elevational view of the fragmentary portion of tire shown in Fig. 1; and

Figure 4 shows the complete tire, partly in dotted lines.

I claim:

The ornamental design for a tire as shown.

GUSTAVE HUBACH.
